UNITED STATES PATENT OFFICE.

FRANK T. PRIMUS AND EDWARD G. EGGLESTON, OF VINTON, IOWA.

CHALK-HOLDER.

No. 814,872.

Specification of Letters Patent. Patented March 13, 1906.

Application filed October 30, 1905. Serial No. 285,111.

To all whom it may concern:

Be it known that we, FRANK T. PRIMUS and EDWARD G. EGGLESTON, citizens of the United States, residing at Vinton, in the county of Benton and State of Iowa, have invented certain new and useful Improvements in Chalk-Holders; and we do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in chalk-holders, forming a convenient means for holding chalk for coating the ends of billiard-cues and adapted to be held in a convenient position adjacent to the table, and comprises a casing adapted to receive a block of chalk and in the provision of a locking-cap adapted to hold the block within the casing, making it impossible to remove the same until the chalk is nearly used up.

The invention consists in various details of construction and combinations and arrangements of parts, which will be hereinafter fully described and then specifically defined in the appended claims.

Our invention is illustrated in the accompanying drawings, in which—

Figure 1 is a perspective view of our improved chalk-holder. Fig. 2 is a sectional view longitudinally through the device; and Fig. 3 is a perspective view of the parts disassembled, two of the parts being in section.

Reference now being had to the details of the drawings by letter, A designates a casing, which may be of any shape, preferably conforming to the shape of a block of chalk commonly used for coating the tips of billiard-cues. Said casing has open ends, one end being provided with a flange A' to retain the block within the casing. Two of the opposite walls of said casing have formed therein indentures B, forming means to receive the angled portions C, formed at the ends of the U-shaped member C'. The arms of said member C' are resilient, and each arm has an indenture D adapted to receive the ends of the oppositely-disposed wings E, which are fixed to the reel F, which reel is adapted to rotate with a spindle K, journaled in the opposite walls of the cap or closure N. Said U-shaped member is held to the inner end of

said closure by means of the threaded end of the eyebolt Q, which passes through the top of the closure and fits a threaded aperture in said member C'. Said closure has two indentures J formed parallel to each other and adjacent to the marginal edges thereof and affording two inwardly-extending ribs which are disposed one upon either edge of said member C', thereby holding the latter securely from turning. One end of said spindle is hollow, the wall thereof being angular outlined in cross-section in order that a key G may fit said aperture and afford means for rocking the shaft for the purpose of throwing the angled portions of said member C' into engagement with the indentures formed in the receptacle which holds the chalk, as shown clearly in the sectional view of the drawings. It will be noted that said member C' is so constructed that the angled ends thereof will normally be out of engagement with the indentures formed in the chalk-holder, but that when the wings on said reel are turned in opposite directions, with their ends engaging the indentures in the arms of the member C', and when the cap or closure is telescoped within the casing, so that the apertures T and T' come into registration with each other, said angled portions C will engage the indentures B in the chalk-holding receptacle.

From the foregoing it will be observed that by the provision of the apparatus shown and described in our invention a simple and efficient means is afforded for locking the block of chalk within the casing, which latter may be suspended by means of a string within convenient reach of a person desiring to use the chalk, and when it is desired to replenish the chalk the same may be done by the simple use of the key, which may be inserted in the hollow spindle on which the reel is mounted, causing said wings to be thrown out of engagement with the resilient arms of said member C', thus causing said arms to withdraw from the indentures B, allowing the closure to be removed.

Having thus fully described our invention, what we claim as new, and desire to secure by Letters Patent, is—

1. A chalk-holder comprising an open-ended receptacle with indentured walls, one end thereof having an inwardly-turned flange, a closure telescoping within said receptacle, a member having resilient angled arms carried by said closure, and means for

throwing the angled ends of said arms into indentures formed in the walls of said receptacles, as set forth.

2. A device for holding chalk comprising an open-ended receptacle, one end of which has inwardly-turned flanges, two of the opposite walls of said receptacle being indentured, a closure telescoping within said receptacle, a U-shaped member fixed to said closure and having resilient arms, the ends of which are angled, and means for throwing said angled ends into said indentures whereby the closure may be locked within the casing, as set forth.

15 3. A device for holding chalk comprising an open-ended receptacle, one end of which has inwardly-turned flanges, two of the opposite walls of said receptacle being indentured, a closure telescoping within said receptacle, a 20 U-shaped member fixed to said closure and having resilient arms, the ends of which are angled, a rotatable shaft journaled within said closure and having oppositely-disposed wings which are adapted to throw the angled 25 ends of said member into said indentures of the casing, as set forth.

4. A device for holding chalk comprising an open-ended receptacle, one end of which has inwardly-turned flanges, two of the opposite walls of said receptacle being indentured, a closure telescoping within said receptacle, a 30 U-shaped member fixed to said closure and having resilient arms, the ends of which are angled, a shaft journaled in the walls of said 35 closure and having one end hollow adapted to receive a key, oppositely-disposed wings upon said shaft designed to engage indentures in the arms of said member whereby the angled ends of said member may be

thrown into indentures in said receptacle, as 40 set forth.

5. A chalk-holder comprising an open-ended receptacle, one end of which has an inwardly-turned flange, indentures formed in the opposite walls of said receptacle, a closure adapted to telescope within the receptacle, a U-shaped locking member having resilient arms which are indentured and provided with angled ends, a screw-eye passing through the end of the closure and engaging 45 said member, a rotatable shaft having oppositely-disposed wings designed to engage the indentures of said arms to hold the angled ends thereof into the indentures in said receptacle, as set forth.

55 6. A chalk-holder comprising an open-ended receptacle, one end of which has an inwardly-turned flange, indentures formed in the opposite walls of said receptacle, a closure adapted to telescope within the receptacle, a U-shaped locking member having resilient arms which are indentured and provided with angled ends, a screw-eye passing through the end of the closure and engaging 60 said member, a rotatable shaft having oppositely-disposed wings designed to engage the indentures of said arms to hold the angled ends thereof into the indentures in said receptacle, and ribs formed in the end of said closure and adapted to hold said member from 65 turning, as set forth.

In testimony whereof we hereunto affix our signatures in the presence of two witnesses.

F. T. PRIMUS.
ED. G. EGGLESTON.
